UNITED STATES PATENT OFFICE.

ROSS M. G. PHILLIPS, OF LOS ANGELES, CALIFORNIA, ASSIGNOR TO IDE HOLSTER COMPANY, OF LOS ANGELES, CALIFORNIA, A CORPORATION OF CALIFORNIA.

ARMY EQUIPMENT.

SPECIFICATION forming part of Letters Patent No. 723,545, dated March 24, 1903.

Application filed September 25, 1901. Serial No. 76,540. (No model.)

To all whom it may concern:

Be it known that I, ROSS M. G. PHILLIPS, a citizen of the United States, residing at Los Angeles, in the county of Los Angeles and State of California, have invented new and useful Improvements in Army Equipments, of which the following is a specification.

An object of this invention is to provide convenient means for carrying a firearm in a most compact form and for ready and immediate service and to facilitate the use thereof under conditions wherein the hands of the user may be temporarily required to be free for uses other than the manipulation of the firearm without danger of losing the firearm.

This invention includes a novel accoutrement by which the firearm is held more ready for instant action.

I propose by means of this invention to enable cavalrymen and infantrymen to so carry a firearm while in action that the hands will be free for use of lance, sword, saber, or the firearm, as occasion may require, without any danger of the loss of the firearm; also, to make it easier for a cavalryman or other horseman to effectively use the firearm with one hand while guiding his horse with the other.

In this invention I may employ an extensible stock, together with a small firearm, which is adapted for ready and convenient attachment to the front end thereof when it is desired to discharge the firearm from the shoulder and to serve as a holster for the firearm when the latter is not in use.

I also propose to apply the invention to firearms in which the stock or shoulder-piece is permanently attached.

I also propose to provide means whereby the firearm at the convenience of the wearer will be held at the belt and when desired can be instantly adjusted to hang immediately under the armpit, so that when the user desires to discharge the firearm from the shoulder he can with one hand bring it into proper position at the shoulder, the shoulder-strap serving as a guide and adjusting device to bring the shoulder-piece or stock of the firearm into position in front of the shoulder for aiming and firing, and in case he drops the firearm it will immediately swing into po-

sition below the armpit ready for immediate action when required. By this arrangement I propose to do away with any danger of loss of the firearm while in action and to provide for using the firearm in a quicker and better way than heretofore. Said shoulder-strap preferably adjustable as to length, and means are provided for the ready and instant adjustment of the firearm from its position on the shoulder to a position at the belt of the wearer, and vice versa.

The invention is applicable in various ways and the shoulder-strap may be extended around the body diagonally from below the armpit over the opposite shoulder, or it may extend from under the armpit up over the shoulder immediately above.

The accompanying drawings illustrate my invention in a preferred form.

Figure I shows the improvement in carrying position. A small firearm is shown in the holster, and the holster is hanging at the belt. Dotted lines indicate the position of the butt of the stock when the firearm is attached to the holster and the same is in position underneath the armpit of the wearer. Fig. II shows the improvement as it appears when in firing position at the shoulder of the wearer. Dotted lines indicate the position into which the firearm will swing beneath the arm when not in use. Fig. III is a view showing a modification of the improvement in firing position on the wearer. Dotted lines indicate the carrying position of the firearm in the principal construction, wherein the shoulder-strap extends diagonally from one armpit over the opposite shoulder. Fig. IV is an end view of the holster, showing the eye and the hook for attachment to the shoulder-strap.

1 indicates a firearm, and 2 a detachable stock therefor. In the construction shown the detachable stock embodies the holster for small firearm, the front end of the holster being constructed to be attached to the hand of the firearm. Preferably the shoulder-strap is attached to the edges of the stock, as clearly shown in Fig. I, at the eye 4 and the loop 5, so that the butt of the stock is held in the position at the shoulder. The eye 4 is adjustably attached by suitable means to the shoulder-strap.

der-strap to bring the butt of the fire-
to the shoulder and to the belt 6, and
versa. Said eye can be attached to and
held from the hook 7 at pleasure to bring
att of the stock 2 into position either at
shoulder or at the belt. I do not limit
vention to the use of the eye and the
or to the particular point at which the
der-strap is attached to the stock. Any
of adjustable attachment between the
and the shoulder-strap may be em-
d, or at pleasure the shoulder-strap may
manently of the length required to bring
att of the firearm to the shoulder and
the armpit. The shoulder-strap is
ably adjustable as to length, as indi-
by the buckle at 8, and the hook 7 for
ing the stock to the shoulder-strap to
the butt of the firearm at the shoulder
wearer is also preferably adjustable on
rap and is adapted to catch in the eye
op 4, as shown in Fig. II, to hold the
of the firearm as required. In case the
der-strap is passed from below the arm-
over the shoulder against which the
of the firearm is to be held means are
ded for preventing the shoulder-strap
sliding off of said shoulder. The loop
ig. III, fastened to the coat of the wearer,
ates a form of such means. 10 indicates
k on the side of the holster to hook upon
elt 6 to keep the holster from swinging
supported from the shoulder.
practice the firearm may be suspended
the shoulder-strap and allowed to hang
belt of the wearer and may be secured
to by the belt-hook 10 until the wearer
s ready for action, whereupon the shoul-
trap will be adjusted to bring the fire-
nto position below the armpit, where it
dy to be brought instantly into use with
hand, leaving the other hand free. If
ed purposely or accidentally, the fire-
wings into position for being caught by
and to again be used.
ferably the detachable stock of the fire-
embodies a holster 2, furnished with an
sible attachment 12 to engage and hold
un.
ndicates snap-hooks for detachably con-
ng the shoulder-strap 3 with the holster.
s not desired to confine this invention to
pecific construction, combination, and
gement of parts herein shown and de-
ed, and the right is reserved to make all
anges in and modifications of the same
ne within the spirit and scope of the in-
on.
the form shown in Fig. III 3' designates
p encircling the shoulder and sliding
gh the loop 9, the firearm being desir-
attached thereto by suitable means, (in-
ed by the snap-hook 13.)
at I claim, and desire to secure by Let-
patent of the United States, is—

1. The combination of a firearm; a shoul-
der-strap; and means for adjustably attaching
the firearm to the shoulder-strap to permit
bringing the butt of the firearm to the shoul-
der and to the belt, interchangeably. 70
  2. In an accoutrement, the combination of
a firearm furnished at its stock with eyes or
loops; a shoulder-strap attached to said eyes
or loops to support the firearm at the belt of
the wearer; and a hook on said strap to catch
one of said eyes or loops to hold the stock of
the firearm adjustably at the armpit and
shoulder of the wearer. 75
  3. In an accoutrement, the combination of
a firearm furnished at its stock with eyes or
loops; a shoulder-strap attached to said eyes
or loops to support the firearm at the belt of
the wearer; and a hook adjustably mounted
on the strap to catch one of said eyes or loops
to hold the stock of the firearm interchange-
ably at the armpit and shoulder of the wearer. 80
  4. An accoutrement constructed to support
a small firearm at the waist and adapted to
be shortened to support the same under the
shoulder of the user. 85
  5. A holster, adjustable means connected
with the open end thereof to support the hol-
ster at the waist or under the shoulder of the
user, and means for detachably attaching the
other end of the holster to a firearm. 90
  6. A holster, the open end of which is pro-
vided with a hook and a ring, an adjustable
strap secured at its ends to the hook and the
ring respectively, and a hook on the interme-
diate portion of the strap for engaging with
the ring and supporting the holster under the
shoulder. 95
  7. A holster, the front portion of the open
end of which is provided with a perforation
and the rear with a hook, a ring in the per-
foration, an adjustable strap detachably con-
nected with the ring and hook, respectively,
and a hook on the intermediate portion of the
strap for engaging with the ring in the hol-
ster and supporting the holster under the
shoulder. 100
  8. A holster provided with an adjustable
strap at the open end and extensible members
to project from the closed end, said members
being provided with means for detachably
connecting them with a firearm. 105
  9. A holster provided with an adjustable
strap at the open end and extensible means at
the closed end for supporting a firearm, and a
hook on one side of the open end for support-
ing the holster at the belt. 110
- In testimony whereof I have signed my
name to this specification, in the presence of
two subscribing witnesses, at San Francisco,
California, this 16th day of September, 1901. 115
